(57) **CLAIM**

I claim the ornamental design for the watch-case, as shown and described.

DESCRIPTION

FIG. 1 is a front perspective view of the new ornamental watch-case of the present invention.

FIG. 2 is a front plan view thereof.

FIG. 3 is a right side view thereof.

FIG. 4 is a back plan view thereof.

FIG. 5 is a left side view thereof.

FIG. 6 is a top view thereof; and,

FIG. 7 is a bottom view thereof.

1 Claim, 2 Drawing Sheets

FIG. 1

FIG. 2

FIG. 3

FIG. 4

FIG. 5

FIG. 6

FIG. 7
